EJECTOR LAMP SOCKET

Morris Schwartz, New York, and William
Castedello, Huntington, N. Y.

Application January 8, 1940, Serial No. 312,900

5 Claims. (Cl. 173—328)

Our invention relates to a lamp socket arrangement, particularly of the type in which the lamp may be readily ejected when desired.

An object of the invention is the production of 5 a lamp socket which is particularly applicable for flash light lamps used in photography.

A further object of the invention is the utilization 10 of a lamp socket in which a lamp may be readily inserted and locked within said socket and said insertion compressing a spring. After said lamp shall have served its purpose said lamp can be ejected from said socket by simply compressing a pair of ears or projections on said socket with the fingers, said movement causing the unlocking 15 of said lamp in said socket, said unlocking causing said lamp to be ejected under the forced pressure of the compressed spring aforesaid.

Flash lamps are commonly employed in the photographic art. The bulbs of said lamps after 20 being fired or flashed are subject to a high temperature for a certain period after the flashing thereof, and while said bulb is subject to said high temperature, the same cannot be handled without burning the fingers.

25 It is often desirable to photograph a number of separate objectives in rapid succession. The replacement of the flashlight bulbs in ordinary type lamp sockets cannot be readily made until the lamp bulb is cool enough to be handled and delay 30 in picture taking is a result therefrom.

By means of our invention the rapid replacement of lamps in the manner as outlined is possible.

In further description of our invention attention is called to the drawing, in which:

35 Fig. 1 shows the lamp socket and bulb in perspective.

Fig. 2 is a cross-section of the socket and bulb arrangement.

40 Fig. 3 is a detail of the shell housing of the lamp socket on a line 3—3 of Fig. 2.

Fig. 4 is a longitudinal section of the shell housing.

45 Fig. 5 shows a detail of the slot through which means the lamp bulb is locked through the medium of the locking pins mounted on the base neck of the bulb, and which upon the turning of said lamp bulb, a pair of slots form an ejecting path therefor.

50 Referring to Fig. 1. The numeral 20 is the lamp bulb, 21 is the base neck of said bulb. 22, 22¹ are the pins mounted on the base neck 21. The foregoing arrangement is that of the usual bayonet lamp bulb.

55 23 as a whole is the socket shell assembly; 23a

is the shell proper of said socket assembly. 24, 24¹ are the insertion slots on the shell 23a, the end of each of said slots has an L-shaped or key locking portion 24a which serves as a locking medium for the pins 22, 22¹ that are mounted oppositely 5 on the base neck 21 of the lamp 20.

On the bottom section of the shell 23a the edge 25 thereof is flanged inwardly, said inward flange forming a support within said shell for the insulating washer 26¹ and the ejector spring 27 which 10 presses against said washer.

Partially surrounding the upper portion of the shell 23a is a releasing collar 27; said collar is split at 27a, and also has two oppositely positioned square shaped apertures 27b. Said apertures are formed by being punched or indented on three sides of said apertures, the fourth side 27c being bent inward. The bent in portion 27c of each one of the apertures 27b serves to act as a limiting 15 stop for the pins 22, 22¹ on the base neck 21 of the lamp 20 and holding said lamp 20 in cocked position 20 preparatory to the ejection thereof upon the application of the spring releasing means which when applied partially rotates the lamp 20, said movement causing the pins 22 and 22¹ of said 25 lamp to move clear of the extension key slot 24a. The aforesaid movement will be further described hereinafter.

27e is a section of the collar 27 which is secured 30 to the shell 23a by means of rivets 27f or other securing means.

The collar 27 is provided with a pair of ears or projections 28, 28¹, said ears having a coiled spring 28a between them. The function of the 35 spring 28a is to preserve a degree of spacing between the ears 28, 28¹ and to cause the section 27k of collar 27 to retract.

The section 27k of the collar 27 has a limiting 40 rotating movement around the shell 23 upon pressing the ears 28, 28¹ together with the fingers. Said section 27k is held in normal position by means of the spring 28a. The bent in portions 27c of the apertures 27b form the limiting stops 45 for the respective pins 22 and 22¹ of the lamp 20 when said lamp is turned clockwise to the limit of movement provided by the bent in portion 27c of the aperture 27b.

Secured to the lower section of the socket assembly 23 is a flanged collar 29, said collar in turn 50 is secured to a screw plug 30, the function of the latter being well-known as a connecting means by screwing into a standard lamp socket.

On the inside of the screw plug 30 is a contact pin 31 which is connected to the lower base sec- 55

tion 32 that is insulated from the shell 30a of the screw plug 30.

The upper section of the spring 27 is secured in position by means of the washer 26¹. The insulated single conductor wire 33 is projected through the insulating washers 26 and 26¹, said wire being bared and flattened into a contact medium at the upper center of the washer 26¹, said contact medium forms an electrical continuity connection with the contact pin 31 and the base contact 34 of the lamp bulb 20.

Operation

The user of the appliance first inserts the flash lamp into the socket arrangement and locking said lamp in the socket in the usual manner of lamp insertions in a bayonet type socket.

After the lamp has been flashed, the bulb thereof becomes considerably heated, and under ordinary circumstances said lamp would be difficult of removal from the socket owing to the heating thereof.

The user in utilizing the present invention simply presses together the ears 28 and 28¹ and against the spring 28a. The aforesaid movement partially rotates the collar 27 which movement causes the lamp 20 and with it the pins 22 and 22¹ to move out of the L-shaped or key locking portion 24a in which said pins were originally set and to move said pins in direct line with the slots 24 and 24¹. In the position as stated there being no obstacle to detain the lamp bulb in said socket, the spring 27 which had been previously compressed upon the insertion of the lamp in its normal setting position in said socket is now free to expand, said spring expansion causing the immediate expulsion of the lamp bulb aforesaid.

The utilization of the invention is best exemplified when used in connection with a photographic camera. After picture exposure in which the flashing of the flashlamp 20 has been utilized, the user of the camera by simply pinching or pressing the ears 28 and 28¹ with the fingers of the right hand against the intervening spring 28a and holding the camera with the left hand will cause the lamp 20 to be ejected from said socket arrangement. In this manner a new lamp can be substituted in lieu of the exhausted lamp without danger of burning the fingers which would be likely when attempting to unscrew the lamp from the lamp socket in the usual manner.

It will readily be seen that our invention can be considerably modified without departing from the spirit thereof. For example, the finger releasing means on the lamp socket may be constructed in various ways since the releasing means aforesaid is simply an arrangement to force the lamp in the socket to revolubly move a certain distance and thereby be cleared of the key locking extension and upon which the lamp is ejected from the socket through the medium of the expansion of the spring within the socket in the manner set forth.

It will furthermore be seen that our invention has an applicability for purposes other than that pertaining to the photographic field. For instance, the ejector socket may be used in connection with illuminated electrical signs, for automobile lighting, or for lighting locations in which it is difficult to remove lamps while said lamps are lighted.

Now having described our invention, what we claim is:

1. In a lamp socket, said socket including a

shell into which the base section of a lamp is inserted, said lamp having a locking pin arrangement thereon, lamp locking means in said socket, said locking means including a longitudinal slot arrangement, said slot arrangement comprising an L-shaped portion, a spring in said socket, said spring being compressed upon the insertion of said lamp into said socket and locked therein; said locking effected by the turning of said lamp in said socket; finger pressed releasing means mounted on said socket, said releasing means engageable with said locking pin arrangement to cause said lamp in said socket and the locking pin arrangement thereon to be revolubly moved out of said L-shaped portion of said longitudinal slot arrangement whereby said lamp is unlocked from said socket and expelled therefrom through the medium of the expansion of said spring in the socket aforesaid.

2. In a lamp socket of the class described, said socket including a shell into which a lamp is inserted, a pair of slots each of which has extended L-shaped portions in said shell into which a pair of projecting pins mounted on the neck of said lamp are fitted upon the insertion of said lamp in said socket, said lamp and the projecting pins thereon being turned in said socket and held in said L-shaped portion of said slots, a spring within said shell that is compressed upon the insertion of said lamp; finger controlling means mounted on said shell, said finger controlling means when moved and coacting with said projecting pins causing the partial rotation of said lamp from its locked or secured position whereby said lamp becomes unlocked and released, said release causing the release of the compression of said spring whereby said lamp is expelled from the socket aforesaid.

3. In a lamp socket including a shell into which a lamp having pin locking means on the neck thereof is inserted, slotted means in said shell, said slotted means including a L-shaped locking portion for locking and holding said lamp in said socket, a spring within said shell, said spring compressed by the insertion of said lamp in said shell; finger controlled means mounted on the outer circumference of said socket, said finger controlled means contiguous to said pin locking means of said lamp, and upon pressure of said finger controlled means to cause said lamp to be rotatably moved and unlocked and thereby released from said L-shaped locking portions of said slotted means whereby said lamp is ejected from said socket through the medium of the expansion of the spring aforesaid.

4. In combination, a lamp socket, said socket to receive a lamp therein having pin locking means on the neck thereof, the insertion of said lamp to cause the compression of a spring within said socket; lamp ejecting means included in said socket, said spring included in said ejecting means, said ejecting means also including finger controlled releasing means, said releasing means contiguous to said pin locking means in said lamp when mounted in said socket, the pressure movement of said releasing means to cause a rotatable movement of said lamp, said movement in turn causing said pin locking means of said lamp to be moved clear of said locking means in said socket thereby causing the expulsion of said lamp from said socket through the medium of the expansion of the spring aforesaid.

5. In a lamp socket, said socket having a shell into which a lamp is inserted, said lamp having locking means thereon that coact with cooperat-

ing locking means in said socket, finger operated releasing means attached to the shell of said socket, said releasing means contiguous to and coacting with said locking means on said lamp, the movement of said releasing means causing the unlocking of said lamp in said socket, and spring means, in said socket, said spring means

being compressed upon the insertion of said lamp in said socket, the compression of said spring means being released upon the unlocking of said lamp thereby causing the expulsion thereof from the socket aforesaid. 5
